UNITED STATES PATENT OFFICE.

ARTHUR I. PLATT, OF BRIDGEPORT, CONNECTICUT, ASSIGNOR TO THE BRIDGEPORT HARDWARE MANUFACTURING CORPORATION, OF BRIDGEPORT, CONNECTICUT, A CORPORATION OF CONNECTICUT.

BOX-OPENER.

1,093,946.

Specification of Letters Patent. Patented Apr. 21, 1914.

Application filed July 15, 1913. Serial No. 779,147.

To all whom it may concern:

Be it known that I, ARTHUR I. PLATT, a citizen of the United States, residing at Bridgeport, county of Fairfield, State of Connecticut, have invented an Improvement 5 in Box-Openers, of which the following is a specification.

This invention has for its object to provide a strong and inexpensive pocket implement forged from a bar which shall be adapted for use as a hammer and a claw and which shall be provided near the claw end thereof with an inwardly and forwardly extending notch so shaped as to form a backwardly projecting horn especially adapted 10 for use in tearing off the retaining bands of metal or wood which are used, to insure safety of the contents, upon large packing cases, and upon smaller boxes and cases as 15 well where the contents are heavy or valuable, and the greatest degree of strength and safety readily attainable is required.

With this and other objects in view I have devised the novel box opener which I 20 will now describe, referring to the accompanying drawing forming a part of this specification and using reference characters to indicate the several parts.

Figure 1 is a perspective illustrating the 25 use of my novel implement in tearing a retaining band from a box; Fig. 2 a plan view of the implement on an enlarged scale, and Fig. 3 is an edge view thereof.

While my novel implement is adapted for 30 miscellaneous uses requiring a hammer and a claw it is especially designed for use in receiving and shipping rooms and places generally where boxes and packing cases are opened and closed, the requirements being 35 for an implement that can be conveniently carried in the hip pocket and readily inserted and removed without catching upon the garment and which in addition to comprising a hammer and a claw for extracting 40 nails shall combine therewith a horn especially adapted for engaging and tearing off the retaining bands upon boxes and packing cases, which cannot be conveniently 45 accomplished by an ordinary nail extracting claw.

10 denotes the shank of my novel implement, 11 a double-headed hammer which is forged at one end of the shank at right

angles thereto and 12 the claw which is formed at the other end of the shank by 55 flattening the metal, tapering the opposite side to a dull edge, tapering the edges thereof outward and providing the usual V-shaped opening indicated by 13, the claw being preferably curved slightly, as shown 60 in Fig. 3.

14 denotes a backwardly projecting horn for loosening and tearing off the retaining bands of boxes and packing cases, as shown in Fig. 1. This horn is formed by forging a 65 forwardly extending V-shaped notch in the edge of the shank back of the claw, said notch being beveled from the upper face of the shank to the lower face thereof, and forging the horn with a blunt point in 70 alinement with the lower face of the shank and in substantial alinement with the edge of the shank to adapt it to catch under and tear off the retaining band, which may first be slightly loosened if necessary by the claw. 75 The notch is necessary in order to enable the horn to be passed under the retaining band as it is required that the horn project but slightly from the line of the side of the implement, so that it will not catch upon the 80 pocket of the user in inserting and removing it.

In using the horn to remove a retaining band the horn is drawn under the band from the inner side and the side of the claw end 85 of the implement is used as a fulcrum in prying off the band, as is clearly shown in Fig. 1.

Having thus described my invention I 90 claim:

An implement of the character described comprising a shank having in its otherwise substantially continuous edge a forwardly inclined notch forming at its forward side an acute angle with said edge and providing 95 a rearwardly inclined horn beveled on its inner side toward one face of the shank and forming a point in substantial alinement with the edge of said shank.

In testimony whereof I affix my signature 100 in presence of two witnesses.

ARTHUR I. PLATT.
